UNITED STATES PATENT OFFICE.

EDWARD FUHRMANN CLARKE, OF BIRMINGHAM, ENGLAND.

FUEL-ECONOMIZING APPARATUS.

1,073,795.

Specification of Letters Patent. Patented Sept. 23, 1913.

Application filed February 24, 1913. Serial No. 750,306.

To all whom it may concern:

Be it known that I, EDWARD FUHRMANN CLARKE, a citizen of Great Britain, and a resident of 5^a Temple Row, Birmingham, 5 county of Warwick, England, consulting engineer, have invented certain new and useful Improvements in Fuel-Economizing Apparatus, of which the following is a specification.

- 10 This invention comprises improvements in smoke consuming and preventing, and fuel economizing apparatus for furnaces and the like, and relates to the type of apparatus in which controllable openings are arranged 15 in the furnace door and are opened by the action of opening the door for stoking and are gradually permitted to close under the influence of a spring or the like which is opposed by a suitable resistance.
- 20 The object of these arrangements is to permit the entry of additional air to effect the combustion of the heavy carbon gases given off from the fuel immediately after stoking and to gradually cut off this additional air supply when the more volatile 25 gases have been given off by the fuel and burned. The arrangements therefore prevent smoke and consume and obtain the additional heat from the volatile gases, which 30 form or assist in forming smoke, thus in addition to preventing a nuisance, economy in fuel consumption is obtained.

With the above and other objects in view the invention consists in general of certain 35 novel details of construction and combination of parts hereinafter fully described, illustrated in the accompanying drawings, and specifically claimed.

On the drawings: Figure 1 is an elevation of the front casting of a furnace front 40 of a boiler with my invention applied. Fig. 2 is a section on line 2—2 of Fig. 1 looking to the left. Fig. 3 is a section on line 4—4 of Fig. 4 looking to the left. Fig. 4 is a similar view to Fig. 1 but with the air inlets closed. Fig. 5 is a part sectional view to a larger scale showing the preferred braking 45 means. Fig. 6 is a cross sectional view on line 6—6 of Fig. 5. Fig. 7 is a cross sectional view on line 7—7 of Fig. 5, and Fig. 50 8 is a cross sectional view on line 8—8 of Fig. 5.

In my invention I arrange an opening or openings *a* in the furnace door *b* and provide pivotal closing flaps *c* for these open-

ings. To enable the closing flaps to make a tight closure I form beads or ribs *d* around the openings *a* and extend the bottom rib of each beyond the upper one and incline the surfaces of both to the same angle to the vertical, see Fig. 2. If the flap *c* of each opening *a* is pivoted above the upper bead *d* thereof, the main body of the flap is to the side of this center and is maintained by its own weight tightly against the surfaces surrounding the opening, see Fig. 3. The openings *a* and flaps *c* are preferably horizontal and the flaps may be mounted by means of lugs *e* through which a hinge pin *f* passes into lugs *g* on the door *b*. The lug *e* on one side of each flap is preferably longer than the other, and is provided with a crank *h* fitted with a pin *i*. A vertically moving connecting rod *j* is provided for simultaneously operating the flaps, see Figs. 1, 2, and 3; 75 and for this purpose it is connected to the crank pins *i* of the flap cranks *h*, so that by raising the bar the cranks *h* are rotated and the flaps *c* raised to admit air through the openings.

To rotate the cranks *h* to operate the flaps I connect the rod *j* to a crank *k* which is mounted on a short axle or stud in a bearing lug *l* on the door *b*. On the other end of the stud is a second crank *m* which is provided 85 with a roller *n* which rests upon the surface of a cam *o* keyed to a spindle *p* working in a bracket *q* on the door frame or casting. On the cam *o* is a projection *r* which is brought around to bear against a projection 90 *s* on the upper hinge strap *t* of the door *b* by the action of a weight *u* (or may be by a spring), see Fig. 4.

The bracket *q* has a platform *v* through which the spindle *p* projects, and upon the spindle above this platform a disk *w* is secured carrying a pawl *x* which is adapted to engage with a ratcheted disk *y* on a gear wheel *z* mounted in bearings from a second platform *l* and thus quite independent of 100 the spindle *p* or its disk *w*, see Fig. 5. The gear wheel *z* is the first of a multiplying train the wheels of which are numbered respectively to their driving relation *z*, 2, 3, 4, 5, 6, 7, and 8, the final pinion 8 being keyed 105 on the spindle 9 of a fan. The gear train will be understood from reference to Figs. 5, 6, and 8, but any suitable multiplying gear may be used.

It will be seen that the gearing and the 110

fan are inclosed within a dust proof casing 10 secured upon the platform *v* of the bracket *q*.

The operation of the device is as follows: 5 As the door *b* is opened for the charging of the furnace the projection *s* carries around the cam *o* from the position shown at Fig. 4, thus turning the spindle *p*, and its disk *w* also, but the pawl *x* simply clicks around 10 the ratchet *y*. The rotation of the cam *o* raises the weight *u* and the tendency is to instantly return the cam when the door closes. Thus far the door *b* with bearing *l* and crank *m* and its roller *n* have simply 15 turned around with the cam as the hinge strap *t* has rotated on the door hinge pin to turn the cam. When the door *b* is closed the strap *t* of course turns in the reverse direction and brings back the projection *s*, and 20 cam *o* under influence of the weight tends to follow the projection *s* but is prevented by the pawl *x* engaging the ratchet *y* and thus connecting the cam through the gear train to the fan. The cam is thus retarded 25 while the door returns, and therefore the roller *n* travels around the surface of cam *o* and encounters the raised path 11 which it rides up to the position shown in Fig. 1 thus rotating the cranks *m*, *h*, and through 30 the connecting rod *j* the cranks *h* also, thereby raising the flaps *c* which cover the air inlets *a*.

The fan traveling at a high speed and doing work by circulating air within the case 35 or cover 10 brakes the action of the weight upon the cam *o* and the return of the cam and consequent closing of the inlets is very gradually effected as is desired.

I prefer to provide means to enable the 40 resistance offered by the fan to be regulated, and these may be as follows: The fan shown at Figs. 5 and 7 is a bladed fan 12 rotating in a volute casing 13 with a cover plate 14 having a central opening 15 for the purpose 45 of providing a feed and an opening in the casing for delivery at 16 (Fig. 7). By closing the feed opening 15 or delivery opening 16 no air is transmitted to the fan which is consequently relieved of work and the blades 50 rotate at a higher speed, and the weight *u* is permitted to be rapid in its action. The reverse action enables air from within the cover 10 to be drawn into the fan and blown out through opening 16 up to the space at 55 the top of the cover 10 again and is thus circulated and the work entailed increases the resistance to the action of the weight *u* and entails slower closing of the flaps *c*. Between these two positions I am able to 60 obtain considerable degrees of regulation so that the operation of the flaps may be suited to circumstances such as the nature of the fuel etc. For closing the opening 15 I have shown a valve plate 17 operated by a 65 screw 18 through the case 10, the screw 18

having a spool or handle member 19' fixed thereto, which handle member is exterior to the case 10.

It is desirable to provide means to insure a regular period of opening of the flaps *c* or air inlets *a* independent of the care of the attendant in opening the door *b*. To this end I provide a raised rib 19 on the platform *v* around disk *w*; this rib has a shaved off end at 20 see Fig. 6, and its function is to receive and depress the tail of the pawl *x* when the door *b* is swung open beyond a certain point. As the door springs open the disk *w* and its pawl *x* travel in the direction of the arrow (Fig. 6 is a sectional plan) and after the point 21 of the rib 19 is reached the tail of the pawl is depressed to such an extent that the nose is clear of the ratchet teeth *y*. Thus when the door is closed the disk *w* and cam *o* are permitted to turn with it under the influence of the weight *u*, until the pawl *x* returns past the point 21 of the rib again, when it is permitted to click into engagement with the ratchet, and the operation is then as set out above.

What I claim then is:

1. The combination with a furnace door provided with a damper opening, and a closure for said opening; of a clock work mechanism arranged to be wound by the opening 95 of the door, means controlled by the clock work mechanism and arranged to open the damper as the door is returned to closed position, said last mentioned means being moved by the clock work mechanism to close 100 the damper after the door is closed, and a governor connected to said clock work mechanism to regulate the speed thereof, said governor including a fan and manually operable means for varying the resistance of 105 the movement of said fan.

2. The combination with a clock work mechanism for automatically closing a damper; of a governor for such mechanism operably connected thereto and comprising a 110 fan, a volute casing surrounding said fan and having an inlet opening at one side, and a movable closure plate to open and close said inlet opening.

3. The combination with a furnace door provided with a damper; of a clock work mechanism arranged to be wound by the opening of the door and controlling the operation of said damper, a governor for said mechanism, and means whereby the governor is operably connected to the mechanism at a predetermined position of the door whereby said damper remains open for a period of time independent of the opening of said door beyond said position.

4. The combination with a furnace door provided with a damper, of an element arranged to be rotated by the opening of the door, of a pawl carried by said element, a ratchet journaled for rotation and adapted 130

for engagement by the pawl, a gear train operably connected to the ratchet and controlling the closing of said damper, and means adjacent the path of the pawl permitting engagement of the pawl with the ratchet until a predetermined point in its movement is reached.

In testimony whereof I affix my signature in presence of two witnesses.

EDWARD FUHRMANN CLARKE.
